(57) **CLAIM**

The ornamental design for a connector for LED package, as shown and described.

DESCRIPTION

FIG. 1 is a side, top, perspective view of the connector for LED package with all elements except for an electrical connector shown in phantom;

FIG. 2 is a top view thereof;

FIG. 3 is a ride side view;

FIG. 4 is a left side view;

FIG. 5 is a front view; and,

FIG. 6 is rear view.

The broken lines showing of portions of the LED package is for illustrative purposes only and forms no part of the claimed design.
